[57] ABSTRACT

A traveling wave maser (TWM) of the comb type is disclosed for operation in the 7-20 GHz frequency range. The TWM is loaded with 0-degree Czochralski grown ruby with its C-axis at angle $\theta=90^\circ$ with respect to the magnetic field. The TWM is pumped in the push-push mode between levels 1-3 and 3-4 with two different frequencies.

MASER FOR FREQUENCIES IN THE 7-20 GHZ RANGE

The invention described herein was made in the performance of work under a NASA contract and is subject to the provisions of Section 305 of the National Aeronautics and Space Act of 1958, Public Law 85-568 (72 Stat. 435; 42 USC 2457).

BACKGROUND OF THE INVENTION

1. Field of the Invention

The present invention is generally directed to a maser amplifier and, more particularly, to a maser amplifier of the comb type with improved gain-bandwidth product and noise-temperature characteristics.

2. Description of the Prior Art

The construction and use of a traveling wave maser (TWM) of the comb type is well known. Such TWMs are described in the literature and in many U.S. Pats., including U.S. Pat. Nos. 3,214,701, 3,296,541, 3,299,364 and 3,486,123, the latter having been issued to one of the applicants of the present application. As is known, in each of these TWMs, an active material is employed. In U.S. Pat. No. 3,486,123 the active material is in the form of slabs cut from zero-degree Czochralski rube with their lengths along the C-axis of the ruby.

The use of ruby in TWMs is well known. For example, the advantages of ruby and its energy level diagrams are described in "Microwave Solid State Masers" by A. E. Siegman, Library of Congress Catalog Card Number 63-12131, particular attention being directed to pages 115 and 116. As stated therein, an angle generally defined as θ of $54^{\circ}44'$ 54.7° between the ruby C-axis and the magnetic field is extremely convenient in certain doubly-pumped maser schemes. This angle value, i.e., $\theta = 54.7^{\circ}$ is known as the double-pump angle. A similar reference is found in Technical Report No. 457 of the Lincoln Laboratory of Massachusetts Institute of Technology entitled, "The Microwave System of the Haystack Planetary Radar" by C.W. Jones, published Oct. 23, 1968.

Although TWMs with ruby cut at $\theta = 54.7^{\circ}$ have been constructed, their construction presents several problems, primarily among them being that of accurate ruby orientation. It has been determined that any minor deviations from the desired value of θ , either due to improper ruby growth, cutting or due to imperfect alignment during construction or during subsequent use results in significant deviations in the pumping frequency required for a particular signal frequency. The signal frequency, in a fixed magnetic field, also experiences significant deviation due to crystal misalignment. Such deviations severely degrade the amplification factor of the maser.

Heretofore, two basic pumping techniques have been used in conjunction with a TWM with ruby (one at $\theta = 54.7^{\circ}$ and another at $\theta = 90^{\circ}$) and push-pull pumping, which is referred to in the afore-mentioned references as double pumping (for $\theta = 54.7^{\circ}$).

In developing a TWM for a range of frequencies from about 7 GHz to 20 GHz, as well as in designing a TWM for lower frequencies in a lower band, referred to as the S-band, it has been discovered that the effects of ruby misalignment are greatly reduced when $\theta = 90^{\circ}$, i.e. when the C-axis is perpendicular to the magnetic field. Indeed, deviations from $\theta = 90^{\circ}$ up to 1° produced only small changes in the pump and signal frequencies. However, in the range of 7 GHz to 20 GHz with ruby at $\theta = 90^{\circ}$, prior art pumping techniques have been found to be quite unsatisfactory. Performance, as represented by measured inversion ratio, was found to degrade as the signal frequency increased above 8.5 GHz. A need therefore exists for a new method of pumping a TWM with ruby at $\theta = 90^{\circ}$ to produce high amplification factors at frequencies above 7 GHz.

OBJECTS AND SUMMARY OF THE INVENTION

It is a primary object of the present invention to provide a new improved TWM for frequencies in the 7-20 GHz range.

Another object of the present invention is to provide a TWM with ruby as the active material, which is simpler to construct than prior art TWMs, and which extends the signal frequency range to about 20 GHz.

- 5 A further object of the present invention is to provide a new method of pumping a TWM with ruby oriented with respect to the magnetic field so as to minimize changes in the pump and signal frequencies due to ruby misalignment.
- These and other objects of the present invention are 10 achieved by providing a TWM with ruby at $\theta = 90^{\circ}$ which is pumped in the push-push mode, with two separate pump frequencies rather than in the single frequency mode (used at $\theta = 90^{\circ}$), or push-pull mode, (used with ruby at $\theta = 54.7^{\circ}$). It has been discovered that unusual and unexpected results, 15 represented by high measured inversion ratios, are achievable when push-push pumping with two pump frequencies is employed with a TWM operable in the 7 to 20 GHz range with the ruby oriented at $\theta = 90^{\circ}$. It is submitted that push-push pumping per se is known and is not regarded as new. However, heretofore, push-push pumping was only performed with a single frequency source. The novelty of the present invention resides in the use of a push-push pumping technique in connection with a TWM, operating above 7 GHz and in particular, such a TWM in which ruby at $\theta = 90^{\circ}$ is employed as the active material and in which two, rather than a single, pumping frequencies are employed. That is, whereas in the prior art only single frequency (at $\theta = 90^{\circ}$) or push-pull pumping (at $\theta = 54.7^{\circ}$), were used with ruby, in the present invention push-push pumping is employed for a TWM with ruby at $\theta = 90^{\circ}$, by the use of two separate pump frequency sources for operation. It has been discovered that such a TWM, between 7 and 20 GHz, in addition to simplified construction due to the reduced alignment problems and improved dynamic stability, has improved tunability, lower noise temperature and higher gain than prior art designs.

The novel features of the invention are set forth with particularity in the appended claims. The invention will be best understood from the following description when read in conjunction with the accompanying drawings.

BRIEF DESCRIPTION OF THE DRAWINGS

FIG. 1 is a simplified block diagram of the present invention;

45 FIG. 2 is a cross sectional view of the TWM of the present invention; and

FIGS. 3 - 5 are diagrams used to highlight the mode of operation and the advantages of the present invention.

50 DESCRIPTION OF THE PREFERRED EMBODIMENTS

The present invention may best be introduced in conjunction with FIGS. 1-3. In FIG. 1, numeral 10 designates a TWM which is shown connected to a signal generator 12 via an input line 13, through which the signal to be amplified is supplied to the TWM 10, and an output line 14, through which the amplified signal is supplied to conventional receiving equipment 15. Also shown is a pump unit 16 which supplies the pump energy to TWM 10. As briefly stated and as will be explained hereafter, unit 16 pumps TWM 10 in a push-push mode with two separate pump frequencies which accounts for the unexpected advantageous results of the present invention.

TWM 10 is assumed to be of the comb type. Structurally, it is similar to the TWM shown and described in U.S. Pat. No. 3,486,123 with only minor design changes introduced to optimize its performance in the X-band. FIG. 2 represents a cross-sectional view of TWM 10 and is analogous to the cross-sectional view shown in FIG. 4 of U.S. Pat. No. 3,486,123. In FIG. 2, numeral 20 represents the main body of the TWM, with a dividing wall 22, numerals 24 designate the comb fingers, and numerals 26 the active ruby material. Numerals 28 designate the isolators, which are strips of polycrystalline yttrium-iron-garnet (YIG), mounted on alumina supports 30. As seen, the ruby material 26 is located on only one side of the

comb fingers 24, while an alumina support material 30 is located on the outside of the comb fingers. Alumina pads 32 space the isolators 28 away from the base of the comb body 20 to prevent the isolator strips 28 from contacting the comb body 20.

As previously stated typically in the prior art, the ruby 26 is cut so that its C-axis is at $\theta = 54.7^\circ$ with respect to the direction of the magnetic field, which is designated in FIG. 2 by arrow 35. This is particularly the case when double-pumping (generally referred to as push-pull pumping) is employed. This axis orientation however is quite critical. It must be accurately achieved and maintained to avoid pump and signal frequency changes. It has been discovered that crystal orientation problems can be greatly simplified and dynamic stability greatly increased by choosing $\theta = 90^\circ$. That is, by placing the ruby's C-axis in a plane which is perpendicular to that of the magnetic field direction. This plane is represented in FIG. 2 by arrow 36 and a direction perpendicular to the plane of the Figure as represented by dot 37.

The ruby orientation with $\theta = 90^\circ$ simplifies the construction of the TWM, and increases its dynamic stability. However, it presents pumping problems when operated above 8.56 GHz with prior art pumping techniques. These pumping problems are solved by the present invention. When operating above 8.5 GHz with ruby with $\theta = 90^\circ$ attempts were made to pump the TWM with known pumping methods. Basically, these include single frequency and push-pull pumping. However, the performance was found to be unsatisfactory due to very low measured inversion ratios. Experiments indicated that performance degrades as the signal frequency increases from 7 to 20 GHz. However, it was discovered that high performance is achieved when push-push pumping with two separate pump frequencies is employed.

FIG. 3, to which reference is now made is a diagram of the energy levels of ruby. The four levels are designated by numerals 1 through 4. It has been discovered that by pumping the TWM 10 with ruby at $\theta = 90^\circ$ with two separate frequencies between levels 1-3 and 3-4, as represented by arrows 41 and 42 high gain is attained between levels 1 and 2, as represented by arrow 43.

The advantages of orienting the ruby with $\theta = 90^\circ$ are best highlighted in conjunction with FIG. 4. Therein lines 45-47 designate changes of signal frequency and two push-push pump transitions for a particular embodiment actually reduced to practice as a function of ruby orientation with $\theta = 90^\circ$. As seen, misorientations of 1° can be tolerated with little effect in the signal frequency or the pump transitions. On the other hand, significant changes in the signal frequency and the pump transitions occur due to misorientations of the ruby when $\theta = 54.7^\circ$ and conventional push-pull pumping is employed. These changes are represented by lines 51-53.

The advantages of the present invention may be further highlighted by the results of various experiments summarized in chart form in FIG. 5. As seen therefrom, when $\theta = 90^\circ$, except near the lower end of the 7 - 20 GHz range, only when push-push pumping is employed are high inversion ratios attained. For example, with a signal frequency of 8.5 GHz and single frequency pumping between levels 1-4 is employed, an inversion ratio of 2.5 was achieved. However, under the same pumping condition with a signal frequency of 16.8 GHz, the measured inversion ratio is extremely low, being -0.1. Similarly with $\theta = 90^\circ$, single frequency of 16.8 and with push-pull pumping between transitions 1-3 and 2-4 with frequencies of 37.4 GHz and 26.5 GHz the measured inversion ratio is only 0.35. On the other hand, the highest measured inversion ratios are attained as long as push-push pumping (between levels 1-3 and 3-4) is employed.

It is thus seen that with ruby at $\theta = 90^\circ$ with a signal frequency of 16.8 GHz satisfactory performance is only obtained with push-push pumping rather than with either of the prior art pumping methods.

It should be noted that in the present invention either pump frequency is higher than the signal frequency.

The TWM system of the present invention in which ruby is oriented with $\theta = 90^\circ$ and is pumped by the push-push method, in addition to simplified crystal orientation and increased dynamic stability has improved tunability, lower noise temperature and higher gain than previous designs. These advantageous properties are due to favorable transition probabilities which exist in ruby near $\theta = 90^\circ$. Combined with a successful pumping technique, the resultant capability to provide a high amplification factor also improves noise temperature and tunability of a maser amplifier.

In one actual reduction to practice a 3 inch comb type TWM was operated at 8.5 GHz with ruby at $\theta = 90^\circ$ with push-push pumping with two pumping frequencies (see third line of FIG. 5). The measured inversion ratio was 3.2, with an electronic gain of more than 30dB. The tunable range was from 7.6 GHz to 8.5 GHz.

A dual TWM (two 3 inch combs, side by side) was also constructed and is in actual field operation. It is tunable from 7.6 GHz to 8.9 GHz. The equivalent input noise temperature was measured to be 7° K at 8450 MHz. Net gain between 30dB and 40dB is obtained by single frequency pumping of the 1-4 transition. However, a 10dB improvement is obtained when the same TWM is pumped in the push-push mode with two separate pumping frequencies.

It should be noted that the use of ruby at $\theta = 90^\circ$ in the 7 to 20 GHz range with push-push pumping need not be restricted to masers of comb-type design. The above technique will produce improvements in performance of any slow-wave structures, or waveguides filled with maser material, or masers of the cavity type.

There has accordingly been shown and described herein a new improved TWM for operation between 7 and 20 GHz. It is appreciated that although particular embodiments of the invention have been described and illustrated herein, it is recognized that modifications and variations may readily occur to those skilled in the art and, consequently, it is intended that the claims be interpreted to cover such modifications and equivalents.

What is claimed is:

1. In combination with a traveling wave maser designed for operation above 7 GHz and including an active maser material oriented therein with its C-axis in a plane perpendicular to the magnetic field of the traveling wave maser, the combination comprising:
a signal source coupled to said traveling wave maser for supplying it with signals to be amplified in said range; and
pump means coupled to said traveling wave maser for pumping it in the push-push mode, with two distinct and separate pumping frequencies.
2. The arrangement as recited in claim 1 wherein said active maser material is zero-degree Czochralski grown ruby.
3. The arrangement as recited in claim 1 wherein said active maser material has four energy levels definable as levels 1-4 and said pump means pumps said traveling wave maser in the push-push mode between levels 1 and 3 and levels 3 and 4 with the signal being amplified between levels 1 and 2.
4. The arrangement as recited in claim 3 wherein the signal frequency is less than either pump frequency.
5. The arrangement as recited in claim 3 wherein said active maser material is zero-degree Czochralski grown ruby.
6. The arrangement as recited in claim 5 wherein said traveling wave maser is pumped by two different frequencies and the signal frequency is less than either pump frequency.
7. In combination with a traveling wave maser of the comb structure designed for operation in a range of frequencies including the range of 10 GHz to 20 GHz and including an active maser material oriented therein with its C-axis in a plane perpendicular to the magnetic field of the traveling wave maser, the combination comprising:
a signal source coupled to said traveling wave maser for supplying it with signals in said range to be amplified therein; and

pump means coupled to said traveling wave maser for pumping it in the push-push mode, with two distinct and separate frequencies.

8. The arrangement as recited in claim 7 wherein the signal frequency is less than either pump frequency.

9. The arrangement as recited in claim 7 wherein said active

maser material is zero-degree Czochralski grown ruby having four energy levels definable as levels 1-4 and said pump means pumps said traveling wave maser in the push-push mode between levels 1 and 3 and levels 3 and 4 with the signal being amplified between levels 1 and 2.
